UNITED STATES PATENT OFFICE.

CHRISTINE PETERSEN, OF EVANSTON, ILLINOIS.

CORSET CLOSURE.

Application filed March 2, 1922. Serial No. 540,386.

To all whom it may concern:

Be it known that I, CHRISTINE PETERSEN, a citizen of the United States, residing at Evanston, in the county of Cook and State 5 of Illinois, have invented certain new and useful Improvements in Corset Closures, of which the following is a specification.

This invention relates to corset closures, and comprises particularly a novel shield 10 attachment or construction adapted to be applied to corsets for the purpose of covering the lacings. It is old to provide a corset closure with a shield for covering the space between the margins which are bridged by 15 the lacings, but these shields have ordinarily been made in one piece, which is objectionable for various reasons, one of which is that it is difficult to adjust or properly position the shield, so that it becomes wrinkled or 20 misplaced. By means of the present invention a shield is provided which is not open to these objections, but which is capable of an adjustment corresponding to the adjustment of the corset lacings, the same laces being 25 used to adjust the corset.

In the accompanying drawings, Fig. 1 is a perspective view of the corset as worn. Fig. 2 is a front view of a section of a corset provided with the shield. Fig. 3 is a back 30 or inside view of Fig. 2. Fig. 4 is a top or edge view.

The general construction of the corset may be of any suitable type. I show a corset which is laced at the front by laces 6, with 35 a section of elastic laces 7 at the bottom. The laces 6 may be made in two sets connecting respectively the upper and lower parts of the corset. The corset will be closed by a line of hooks 8 in a well known manner, 40 between the body of the corset and a strip 9 which has eyelets 10 to receive the laces above referred to, these laces connecting said strip to an opposite strip 11 having eyelets 45 12 to receive the laces. This structure is well known in the art.

To form the shield I provide a pair of flaps 13 one of which is sewed along its fixed edge as at 14 to the strip 9 and the other of which is sewed along its fixed edge 50 as at 15 to the body 16 of the corset. The free or meeting edges of the flaps 13 may be provided with steels or stays indicated at 17, and with a plurality of eyelets 18 and 18^a, the latter being located near the upper end 55 of the flaps and the former near the lower

end. I show three eyelets 18 at the lower end of the flaps, but one or any other number of eyelets may be used on each flap.

The purpose of the flaps 13 is to cover or bridge the space crossed by the laces 6, and 60 the edges of the flaps 13 are capable of being drawn together in all adjustments of the laces. This drawing together is effected by the same laces 6 as are used for adjusting the corset, and I accomplish this result by extending the laces 6 through the eyelets 18 and 18^a of the flaps, the upper section of the laces extending through the eyelets 18^a and the lower section of the laces extending through the eyelets 18. That is to say, these 70 laces extend through the eyelets of the corset body and also through the eyelets of the flaps, as clearly appears in Fig. 4, the laces being crossed to pass from one to the other.

Now, when tension is applied on the laces, 75 which tension is resisted by the pressure on the corset, the first action is to draw together the flaps 13, as shown in Figs. 3 and 4. This forms the shield. Then, as the laces are taken up, the body of the corset is drawn 80 together in the usual manner. This action is effected both at the top and bottom of the shield, and when the laces are finally adjusted and tied the whole forms a complete 85 adjustment not only of the corset body but also of the shield flaps, and the laces hold the shield in proper and fixed position and prevent the same from becoming misplaced or wrinkled. After the laces are once adjusted the corset may be applied or removed 90 without disturbing this adjustment, by unhooking the same as usual.

An adjustable shield so constructed has 95 many advantages over the loose one-piece shields ordinarily employed.

I claim:

1. The combination with corset sections having margins provided with eyelets, of a shield comprising a pair of flaps both of which are connected to and project beyond 100 the respective margins on the inside of the sections, whereby the edges of the flaps will abut with each other and close the space between the sections in all positions of the latter, and laces connecting the margins of 105 the corset sections and also the margins of the flaps.

2. The combination with a corset provided with laces, of a shield consisting of two flaps connected respectively to and project- 110

ing respectively beyond opposite margins of the corset body, both of said flaps being located on the inside of the corset body and adapted to abut at their edges in all adjustments of the body, and laces connecting the margins of the corset body and also the margins of the flaps.

In testimony whereof, I affix my signature in presence of two witnesses.

CHRISTINE PETERSEN.
